UNITED STATES PATENT OFFICE.

JAMES M. CONNER, OF NEW YORK, N. Y.

DESIGN FOR A FONT OF PRINTING-TYPE.

SPECIFICATION forming part of Design No. 12,401, dated August 9, 1881.

Application filed June 16, 1881. Term of patent 14 years.

To all whom it may concern:

Be it known that I, JAMES M. CONNER, of the city, county, and State of New York, have invented and produced a new and original Design for a Font of Printing-Type, of which the following is a specification.

The nature of my design is clearly shown in the accompanying typographic impression, to which reference is made; and it consists of an unshaded letter somewhat similar to the class known as "old style."

In the A the cross-line is inclined, as shown. In the letters B, D, P, and R the upper left-hand of the rounding portion of the letter terminates in the heavy dot, as shown. In the C, F, and G, this dot termination is found at the upper right hand of the letter, and both terminations of the E, S, T, Z, and \$ have it. The E and F have upon the right a vertical line extending downward and terminating upon the right in a dot, and the left-hand portion of the H and X is extended below the line, and has upon the right a short horizontal line with dot termination. The letter J has its curved portion flattened out, and is followed by a short inclined line having dot termination upon the left. The lower right-hand portions of the K and R consist of the inclined lines, followed upon the right by short horizontal line with dot terminations. The L, upon the right, is followed by the short curved line with dot termination upon the right, and the left-

hand up-and-down portions of the M and N are extended below the line, and curve to the left with the dot termination. The tail of the Q consists of the looped line crossing the lower portion of the letter, which is flattened out below the letter, and is followed on the left by a short horizontal line with dot termination. In the U the left-hand portion of the letter is gradually widened until it reaches its upper part, where it is thinned, curves to the left, and has the dot termination, as shown. The upper right-hand portion of the Y has the dot termination upon the right of its base. In the symbol & the central portion is looped, as shown. Both terminations are gradually widened, and from the upper termination proceeds the curved line with dot termination. The dot termination is found in the figures 2 and 7 upon the upper left hand, and in the 3 and 5 upon the lower left hand. In the figure 2 the base-line is gradually widened as it approaches the right-hand termination, and the lower part of the 9, upon the left, is flattened out.

Having now described my invention, what I claim as new is—

The design for a font of printing-type, as shown and described.

JAMES M. CONNER.

In presence of—

WM. C. CONNER,
MARTIN F. B. CONNER.
